LAMP CONSTRUCTION

Joseph S. McInnis, Chicago, Ill., assignor to McInnis and Company, Incorporated, Chicago, Ill., a corporation of Illinois

Application July 25, 1956, Serial No. 599,996

3 Claims. (Cl. 240—83)

My invention relates to table lamps and similar devices.

My invention relates more particularly to table lamps of the type that have a self-contained fluid container with a lamp chimney, base, and wick holder attached thereto, and which are adapted to be used for the lighting of individual tables in dining rooms, cocktail lounges, terraces, and for home use as a night light or for decorative effect in dens or television rooms.

The principal object of my invention is to provide an improved construction of table lamp of the type described which includes a self-contained fluid container, lamp chimney, base and wick holder, the same being positioned in a decorative and protective base and shade assembly.

A further object of the invention is to provide an improved table lamp and shade assembly of the type described which not only acts as a receptacle for the fuel container, wick holder and chimney, but also acts as a protective guard so that when the same is knocked over the parts will not become disassembled or broken, nor will it be possible to accidentally cause fires by reason of the flame and fuel coming in contact with tablecloths or other combustible substances.

Other objects and advantages will be more apparent from the following description wherein reference is had to the accompanying drawings, upon which:

Fig. 1 is a vertical cross-sectional view through my improved lamp structure showing the fuel container, wick holder and chimney positioned therein;

Fig. 2 is a side elevational view of the lamp shade assembly;

Fig. 3 is a bottom plan view thereof;

Fig. 4 is a plan view of the base extension which operates as a support and container for the removable fluid container; and

Fig. 5 is a side elevational view thereof.

In the embodiment of the invention which I have chosen to illustrate and describe, I have shown a table lamp which may include a lamp base member 10 made of sheet metal and formed with a medial upwardly tapering post portion 12 which has a medial opening 14 therethrough. The base extension 16 may also be a sheet metal stamping that has an upper open end 18, a cylindrical shell portion 20 terminating in a shoulder 22, and a chamber 24 therein for the reception of a fluid container 26. The fluid container 26 is adapted to rest upon a shoulder 28 adjacent the bottom of the member 16, the same being inwardly flared and provided with a bottom wall 30 having a central bore 32 therein.

A hollow bolt member 34 may be screw-threadedly mounted in a weight 36 positioned in the base member 10, the bolt extending upwardly through the openings 14 and 32 and provided with a nut member 38 for fastening the base 10 and the base extension 16 rigidly together. A piece of felt 40 may be adhered to the bottom of the weight 36 to cover the lower opening of the base 10.

The fuel lamp ensemble may include the container 26

2

previously described and a combined wick holder and lamp chimney base 42 provided with the usual spring finger members 44 for supporting a glass chimney 46 in position thereon. In order to keep the lamp chimney from falling out of its holder if the lamp should be tipped over, I have provided a split spring ring 48 which fastens about the fingers 44 to frictionally hold the chimney from removal.

The decorative and protective lamp shade 50 may have a cylindrical shell portion 52 adjacent its upper end terminating in a flange 54 from which the frusto-conically shaped shade portion 56 extends down to a point adjacent the top of the base extension 16, the edge 58 being curled over as shown to receive a cylindrical split spring ring 60 that is snapped into position therein to fixedly connect the lamp shade to the ring.

As best shown in Figs. 1 and 3, the ring 60 has radially extending arms 62 welded or otherwise secured thereto and extending inwardly to be welded or otherwise secured to the top of a metal ring member 64. The ring member 64 encircles a fiberglas tube 66 to which the same is fastened by rivet members 68, so that the tube 66 and the shade 50 are thus connected together when the spring ring 60 has been snapped into place in the inside of the shade 50.

The tubular member 66 extends down inside of the base extension 16 and seats upon the shoulder 22 of the cylindrical portion 18 thereof, the tubular member preferably having a snug or tight fit inside of the base extension so that in normal use the parts will not be separated, but can only be separated by a direct pull upwardly on the shade and tubular extension.

With this construction it can be seen that the table lamp is assembled by attaching the base extension to the base by means of the bolt 34. After this has been done, the fuel container and lamp chimney assembly can be set in the base extension, the bottom of the container resting on the shoulder 28 and preferably fitting snugly within the chamber 24. The lamp shade assembly, which consists of the frusto-conical shade member, can be assembled to the spring ring 60, to which the shoulder ring 64 and tubular extension 66 are attached. In this condition the tubular extension is pressed into the top of the base extension 16 in a snug fit, and the lamp is thus assembled.

In the event that the lamp assembly is accidentally tipped or knocked over, the shade will prevent the glass chimney from becoming broken, and the spring ring 48 on the chimney holder will prevent the same from dropping out of the assembly. It can thus be seen that I have provided a lamp construction that is easily and quickly assembled, and one that is sturdy and durable.

While I have illustrated and described a specific embodiment of the invention, it will be apparent to those skilled in the art that changes and modifications may be made in the exact details shown and I do not wish to be limited in any particular; rather what I desire to secure and protect by Letters Patent of the United States is:

60 1. A lamp construction comprising a base in the form of an inverted shallow dish having an upwardly tapering hollow post portion thereon, a central opening through the top of said post portion, a hollow generally cylindrically shaped base extension portion having an in-turned shoulder adjacent its upper open end, a second in-turned shoulder adjacent its lower end, the lower end of said extension being closed and having a central opening therethrough, a weight positioned in said base, a bolt screw-threadedly mounted therein and extending upwardly through said openings and provided with a nut to fasten said base and base extension together, a fuel con-

tainer, chimney base and chimney positioned in said base extension and resting on said second inturned shoulder, a shade for said chimney, said shade having radial rods extending inwardly, a cylindrical tube connected thereto and adapted to be snugly fitted into the upper end of said base extension with its lower end resting on said first shoulder.

2. A lamp construction comprising a base in the form of an inverted shallow dish having an upwardly tapering hollow post portion thereon, a central opening through the top of said post portion, a hollow generally cylindrically shaped base extension portion having an inturned shoulder adjacent its upper open end, a second inturned shoulder adjacent its lower end, the lower end of said extension being closed and having a central opening therethrough, a weight positioned in said base, a bolt screw-threadedly mounted therein and extending upwardly through said openings and provided with a nut to fasten said base and base extension together, a fuel container, chimney base and chimney positioned in said base extension and resting on said second inturned shoulder, a shade for said chimney, said shade having radial rods extending inwardly, a cylindrical tube connected thereto and adapted to be snugly fitted into the upper end of said base extension with its lower end resting on said first shoulder, a split spring ring secured to the outer ends of said radial rods, said split ring connecting said shade and said tube together.

3. A lamp construction comprising a base in the form
